UNITED STATES PATENT OFFICE.

PHILIP SAMUEL SPILLER, OF AUSTIN, TEXAS, ASSIGNOR OF ONE-HALF
TO HORACE P. HALDEMAN, OF AUSTIN, TEXAS.

GENERATING OIL-BURNER.

SPECIFICATION forming part of Letters Patent No. 790,666, dated May 23, 1905.

Application filed October 12, 1904. Serial No. 228,182.

To all whom it may concern:

Be it known that I, PHILIP SAMUEL SPILLER, a citizen of the United States, residing at Austin, in the county of Travis and State of Texas, 5 have invented a new and Improved Generating Oil-Burner, of which the following is a specification.

My improvement relates to apparatus by which steam is generated and petroleum or a 10 hydrocarbon reduced to vaporous condition and mixed or combined with the steam and in highly-heated condition burned for heating, lighting, or other purposes in the arts.

The invention consists of the special construction, arrangement, and combination of features, which will hereinafter be fully described, and shown in the accompanying drawings. The novelty thereof will be pointed out in the appended claims.

20 In the drawings, Figure 1 is a view of a stove, part in section, with my burner arranged therein. Fig. 2 is a plan view of my improved burner, the same being shown part broken away and in section. Fig. 3 is a central vertical transverse sectional view through the burner. Fig. 4 is a detail view showing a 25 broken-away portion of the gas-chamber with the three-blaze burners employed by me, and Fig. 5 is a perspective view of the hood forming a part of my improved burner.

In the practice of my invention I employ a casting A, having an inner substantially serpentine steam passage-way B leading upwardly from the inlet end or edge to near the 35 top end or edge thereof and then downwardly into a mixing-chamber D through the passage-way E.

F denotes an inner upwardly-disposed oil or gas passage-way leading from an inlet-opening G at the lower end or edge of the casting A and extending to a point above the mixing-chamber D, from whence by a return passage-way H, leading into the mixing-chamber back of the delivery end of the steam passage-way E, substantially as shown in Fig. 2.

40 I employ a tank I, supported on the stove, substantially as shown in Fig. 1, and convey water therefrom through a pipe I', leading into the receiving-opening G. Flow of oil

through the pipe J' is controlled by a pin or other suitable valve J².

J denotes a suitably-supported elevated tank, from which oil is conveyed through a pipe J', leading into the receiving-opening G of passage-way F. A cut-off valve J² is arranged in the pipe J', for the purpose as will be understood.

In the make-up of my invention a gas-retort K is located below the mixing-chamber D and both thereof made communicating 60 through a passage-way K'. The mixing-chamber, as also the retort, is preferably cast in one piece with the casting A, though they may be constructed separately and secured thereto by approved means. In the ends of 65 the mixing-chamber and retort I arrange removable clean-out plugs K². On the front side of the casting A, I arrange spaced projecting walls or flanges L, connected at their lower ends by a projecting shelf or plate L'. 70 I provide the upper side of the gas-retort K with a series of openings K³ (see Fig. 4) and arrange therein triangular-shaped pins K⁴, leaving a series of gas-outlet passage-ways K⁵, whereby upon ignition of the issuing gas a 75 multiplicity of flames will be had at each of openings K³.

In further carrying out my invention I employ a hood M. (More clearly shown in Figs. 3 and 5.) The hood is constructed with a middle curved portion M', having its inner side made concave at M² and adapted when the hood is arranged in place on the shelf L for providing a combustion-space M³, substantially as shown in Fig. 3. The hood has side 80 flanges M⁴, and the upper middle portion is set back, providing a flame passage-way or hot-gas exit M⁵ from the combustion-space M³. For supplying air into the combustion-space just mentioned the hood may have a series of openings M⁶ in its body portion and its lower edge be constructed having an opening M'. A flange M⁸ is provided at the lower edge of the hood and the same be arranged forming, with the shelf L, an air feeding or 90 guiding passage-way M⁹, leading to the opening M'. 95

The construction of my improved generat-

ing oil-burner will be understood from the above description. It may be placed in any form of stove or fireplace and used with minimum care and expense.

5 Fig. 1 of the drawings shows my burner arranged in a heating-stove patented by me.

In the use of my invention water is fed through the pipe I' into the serpentine passage-way B about one hundred and twenty 10 drops per minute by regulation of the valve I² and upon its passage through the serpentine channels B of Fig. 2 is decomposed into steam. The wet steam now passes through the serpentine passage-way B and by heat of 15 the gas-flames in the casting A is superheated and delivered into the mixing-chamber D through the inlet end E of the passage-way B.

Oil is fed through the pipe J' with proper 20 regulation of the valve J². The oil is converted into gas by heat of the hot-air channels 3 4, (G and D in Fig. 2,) and the gas thus produced passes up the passage-way F and through its delivery end H into the mixing-chamber D, just back of the steam-entrance 25 thereto, as above described. The gas and superheated steam becomes thoroughly mixed in the chamber D and from thence passes into the retort K, to be burned during passage through the openings K³, ranging around the 30 pins K⁴, which openings are intended to form a plurality of blazes at each pin. Combustion of the issuing gas is rendered more complete by feed of air through the draft-opening 5 of the stove 1, the passage-way M⁹, and the opening M⁷. By admixture of air as just described a blue flame is produced and by further feed of the air through the openings M in the hood is further improved, adapted for effectively 35 heating the whole casting. It will be under-

stood that the gases of combustion are slightly 40 stored in the space M⁷ by retarding action of the reduced passage-way M⁹.

Having thus described my invention, what I claim as new, and desire to secure by Letters Patent, is—

1. The combination of the casting having an upwardly-leading serpentine steam passage-way, a mixing-chamber in open communication with said serpentine passage-way, a gas passage-way leading into the mixing-chamber, at a point back of the serpentine delivery thereto, a retort in open communication with the mixing-chamber and having jet-openings, oil and water feeding means, and means for supply of fresh air to the gases after 55 they issue from the jet-openings, substantially as described.

2. The combination of the casting having a serpentine steam passage-way therethrough, and spaced projecting walls on the casting, 60 with a hood constructed to leave a combustion-space when arranged in place on said casting, the hood having air-openings as specified, said casting having an oil-gas passage-way, and a mixing-chamber and a retort, in open 65 communication with said gas and serpentine passage-ways, substantially as described.

3. The combination with the casting having a serpentine steam-passage, an oil-passage, a mixing-chamber and a retort, and oil and water feed or supplying means as specified, of a hood constructed with a concave rear side, an opening at its lower end, and jet-openings in its body portion, substantially as described.

PHILIP SAMUEL SPILLER.
